UNITED STATES PATENT OFFICE.

JOHN N. HARSON, OF PROVIDENCE, RHODE ISLAND.

DESIGN FOR A HAT-MARKER.

SPECIFICATION forming part of Design No. 28,258, dated February 8, 1898.

Application filed December 23, 1897. Serial No. 663,266. Term of patent 3½ years.

To all whom it may concern:

Be it known that I, JOHN N. HARSON, of Providence, in the county of Providence and State of Rhode Island, have invented and produced a new and original Design for Hat-Markers, of which the following is a specification, reference being had to the accompanying drawing, forming part thereof.

The drawing is a representation of a hat-marker illustrating my new design.

The leading features of my new design for hat-markers consist in the general configuration of the body portion, the lateral projections therefrom, and the members extending upwardly from the projections.

In the drawing, 5 indicates the body portion, the edge and the surface portion adjacent to the edge having a simulation of foliated ornamentation which extends outward onto the projections 6 6. From these projections the members 7 7 extend upward.

What I claim is—

The design for a hat-marker as herein shown and described.

JOHN N. HARSON.
